UNITED STATES PATENT OFFICE.

WILLIAM G. BUSSE, OF BROOKLYN, NEW YORK.

MEANS FOR PROPELLING BOATS.

No. 857,868.

Specification of Letters Patent.

Patented June 25, 1907.

Application filed March 22, 1906. Serial No. 307,394.

To all whom it may concern:

Be it known that I, WILLIAM G. BUSSE, a citizen of the United States of America, and a resident of the borough of Brooklyn, in the county of Kings and State of New York, have invented certain new and useful Improvements in Means for Propelling Boats, of which the following is a specification.

The invention relates to removable, mechanical means of propulsion for small boats and the like, and the principal features of my improvements may be summarized as follows: 1. Propeller shafts, carrying propellers, and adapted to be removably connected to the gunwale of a boat, as at both sides thereof. 2. Means enabling the propeller shafts to be adjusted in length. 3. Hand operated mechanical means for rotating the propellers. 4. Means for steering the boat by manipulating the propellers alternately at either side of the boat.

In the drawings accompanying this application, Figure 1 is a side elevation of a boat fitted with my improvement. Fig. 2 is a front view thereof. Fig. 3 is an enlarged elevation of the propeller, with its operating shaft, mechanism, and means of connecting to the side of a boat. Fig. 4 is a section on the line 4—4 of Fig. 3. Fig. 5 is a partial, sectional view of the propeller shaft and tubing. Fig. 6 is a side view of the complete apparatus. Fig. 7 is an enlarged, sectional detail of the propeller driving mechanism, and Fig. 8 is a detail of a clamp.

Briefly my invention consists of a pair of propellers, attached to the ends of propeller shafts that are removably attached, one at each side of a boat, and depend therefrom into the water, a crank for each propeller shaft being provided within the boat whereby the occupant of said boat may cause said propellers to be rotated to propel and steer the boat. To this end I provide a clamp, as A, adapted to be removably attached to the gunwale a of a boat, as by a screw a'. The clamp has the aligned bearings a² for a crank shaft a³, which carries bevel gear a⁴, and has a crank a⁵. The screw a' impinges against a clamp plate B, which lies against the outer surface of the gunwale, with a lip b extending beneath its under surface. Screws b' b', passed through threaded lugs at the upper portion of plate B, and which bear upon clamp A, assist in securing clamp A against vertical displacement. Clamp A has a pendant plate A', having means of attachment to

a hub c upon a tube C, as by the slot c⁶ fitting over stud c', the screw a⁷ and lever a⁸. By such means the tube C can be readily attached to and removed from the clamp A. 60 Slidable in tube C is a snugly fitting inner tube D, a slot c⁹ in tube A, and a set screw d enabling said tube D to be adjusted longitudinally to provide a desired length of tubing.

A hollow block E, removably secured in 65 the upper end of the tube C, as by screws e², is provided with rollers e³, forming a bearing for the upper end of propeller shaft F. This propeller shaft F has a groove f which receives a spline g carried by a telescoping tube 70 G that forms a part of the propeller shaft, and is adapted to extend its length. Thus, as will be observed, the length of both the propeller shaft and its tubular casing may be adjusted to suit the conditions affecting the 75 use of my improvement. The lower portion of tube D is provided with roller bearings d' for tube G, which latter carries the bevel gear H. Tube D also carries an extension frame or bracket D', having the journal bearing d² 80 for shaft I, which latter carries propeller J at one end, and bevel gear i at its other end, in mesh with the bevel H. A brace rod K, extending from the lower end of tube C to the gunwale of the boat, is there secured by a 85 clamp L (see Fig. 8) and serves to maintain the set position of the propeller tubes against the leverage exerted through the action of the propeller.

The crank a⁵ extends into the boat in position for its handle to be conveniently turned by a person sitting on a transverse seat, in the manner of a rower. As two of these propelling devices are employed, one at each side of the boat, a crank handle is provided 95 for each hand of the operator, who can, by turning his cranks separately, and by reversing them control the operation of the boat in any direction, besides being able to propel it at a good rate of speed. 100

It will be observed that the tube C having the extensible tube D is, when attached to the gunwale of the boat, disposed vertically, and that the propeller shaft I is supported from the tube D by the bracket D' at right angles to said tubes C D. By these means the propeller, when rotated through the medium of the bevel gears H i and their allied parts, exerts a moving influence to the boat in a horizontal plane. It will further be noted that by this arrangement the device may be connected to the boat by clamping

at any desired position longitudinally of the gunwale of the boat. Thus if it is desired to operate several pairs of propelling devices, they may be placed at different points along 5 the sides of the boat in positions to be actuated by various occupants of such boats. A feature which lends itself to the convenient application of this device is the use of the clamp A, whereby the apparatus may be secured in place, and shifted and readjusted in the simplest and most expeditious manner possible, as is obvious.

The brace K having its securing clamp L serves a most important function, in that 15 the pressure created by the propeller which naturally tends to strain the tubes C D through the sidereal force thus exerted upon them, is counteracted by the strength and steadiness imparted to said tubes through 20 the medium of said brace. A further important feature of this apparatus consists in the fact that it can be conveniently dismembered and the several parts packed into a small compass.

25 I claim:

1. Propelling means for boats comprising an extensible shaft, means detachably supporting said shaft vertically from the gunwale of a boat, a propeller shaft disposed 30 right angularly at the lower end of said vertical shaft, a propeller carried thereby, a bearing for said propeller shaft, an angularly disposed bracket supporting said bearing from the lower end of said vertical shaft, and 35 means for turning said propeller shaft.

2. Propelling means for boats comprising an extensible shaft, means detachably supporting said shaft vertically from the gunwale of a boat, a detachable brace extending 40 tangentially from a lower point on said shaft to the gunwale, a propeller shaft disposed

right angularly at the lower end of said vertical shaft, a propeller carried thereby, a bearing for said propeller shaft extending from said vertical shaft, and means for turning 45 said propeller shaft.

3. Propelling means for boats comprising a hollow shaft composed of outer and inner telescoping tubes, a clamp detachably supporting said shaft vertically from the gunwale of a boat, a rod rotatably supported within said hollow shaft, a gear upon said rod, a crank-shaft mounted in bearings in 50 said clamp, a gear on said crank-shaft meshing with the gear upon said rotatable rod, an extensible tube sliding on said rotatable rod, a propeller shaft rotatably supported from and at right angles to said hollow vertical shaft, and intermeshing gears respectively upon said extensible tube and propeller shaft. 55

4. Propelling means for boats comprising a hollow shaft composed of outer and inner telescoping tubes, a clamp detachably supporting said shaft vertically from the gunwale of a boat, a detachable brace between 60 said hollow shaft and the boat, a rod rotatably supported within said hollow shaft, a gear upon said rod, a crank-shaft mounted in bearings in said clamp, a gear on said crank-shaft meshing with the gear upon said 65 rotatable rod, an extensible tube sliding on said rotatable rod, a propeller shaft rotatably supported from and at right angles to said hollow vertical shaft, and intermeshing gears respectively upon said extensible tube 70 and propeller shaft.

Signed at New York this 6th day of March 1906.

WILLIAM G. BUSSE.
